UNITED STATES PATENT OFFICE

MARTIN BLAU, OF ERFENSCHLAG, NEAR CHEMNITZ, AND EMIL FREYTAG, OF ZWICKAU,
GERMANY

FOUR STROKE CYCLE ENGINE

Application filed April 5, 1927, Serial No. 181,189, and in Germany April 9, 1926.

Our invention relates to internal combustion engines and more particularly to an improved engine of the four stroke cycle type.

The construction of certain internal combustion engines especially of the four stroke cycle type, is objectionable for the reason that the channels or ports for the admission of the fuel and air mixture are of a considerable length and provided, in most cases, with valves, whereby the movement of the fuel and air mixture towards and to the cylinder or cylinders will be retarded, so that incomplete admission or filling of the cylinders ensues. This defect is the more objectionable in engines particularly designed and intended for high degrees of admission and in which, therefore, the crank case is utilized for a preliminary compression, that is the production of a previously compressed mixture.

The object of our invention is to remedy this defect and with this object in view we provide comparatively short ways or channels for the admission of the fuel and air mixture, and we dispose such channels in a manner which is particularly suitable for ensuring practical advantages such as economy and reliability or commercial and relative efficiency, in engines of quite a variety of constructional modifications.

Other detailed features of the invention will be hereinafter specifically described and then pointed out in the claim.

The inventive idea involved, therefore, is capable of expression in a variety of mechanical forms, three of which for the purpose of illustration are shown in the accompanying drawings, but it is to be understood that said drawings are for the purpose of illustration only, and not for the purpose of defining the limits of the invention, reference being had to the claim for this purpose.

In said drawings Figure 1 is a sectional view of the cylinder casing of an engine constructed according to the present invention;

Figure 2 represents a similar section of the same taken on a plane perpendicular to that of Figure 1; Figure 3 is a sectional view of the cylinder casing of a modified construction (four-stroke cycle engine); Figure 3^a represents the same type with slight modifica-

tions as is suitable for operation according to the two-cycle engine; Figure 4 illustrates diagrammatically the same sectional view for purposes of showing the operation of the engine; Figure 5 represents a longitudinal section of a two-cylinder four stroke cycle engine embodying another modification of the present invention; Figure 6 illustrates in section a portion of the one cylinder shown in Figure 5 on an enlarged scale and with the piston in a different position; Figure 7 is a view similar to Figure 6, but with the piston in a third position; and Figure 8 is a sectional view of the engine shown in Figures 5 to 7, but modified to form a compressor.

Referring to the embodiment of the invention shown in Figures 1 and 2 the engine substantially comprises a cylinder 1, a compression chamber 2 integral and communicating with the cylinder 1, an admission valve 3 located in the wall of the said chamber, an exhaust valve 4, a piston 5 and a crank case 6.

As hereinbefore mentioned, the purpose aimed at by the present invention is to ensure a particularly high compression and efficiency and for this reason the crank case is utilized as an auxiliary means for charging the cylinder. An essential feature of the invention resides in the short admission conduit or channel 9 immediately connected, for communication, with a carburetor (not shown) and having two branches 7 and 8 the length of which, taken both together, is approximately equal to the length of the stroke of the piston. It will be seen that no valves or any other shutting-off gears are provided in the channel for the admission of the fuel and air mixture or in the two branches thereof, so that just owing to the fact that any such obstacles are dispensed with, the charge will have a thoroughly free passage to flow without restraint into both the compression chamber and the crank case.

The operation of the engine is as follows: Supposing the piston 5 has just accomplished the compression stroke so as to occupy the position shown in Figures 1 and 2. Now, due to the movement of the piston towards the compression chamber a vacuum has formed

in the crank case and fuel and air mixture is drawn into the crank case 6 by suction through the branch 8 of the channel 9. In or during the subsequent working stroke of 5 the piston the charge in the crank case is compressed and caused to flow, when the working stroke is finished, through an overflow channel 10 into the working space of the cylinder, after the exhaust valve 4 had 10 previously opened. The fresh charge thus admitted into the cylinder acts to expel the exhaust gases or products of combustion from the cylinder and to fill the compression chamber 2 after the subsequent return or inward 15 movement of the piston. On the next outward movement of the piston, that is the suction stroke, fuel and air mixture is drawn in through the branch 7 of the channel 9 and the admission valve 3, so that, at the moment 20 the piston has finished its suction stroke, a quantity of charge is contained in the cylinder, which comprises two different mixtures of charge viz: the crank charge and the charge coming from the carburetor. At the same 25 time, however, as the piston carried out its outward or suction stroke, as described, again the fuel and air mixture contained in the crank case has been compressed and caused to flow over, at the moment a slot 11 provided 30 in the piston wall has moved down so far as to register with the orifice 10¹ of the channel 10, into the cylinder and mix with the charge already contained therein, so that the total 35 charge comprises three single charges, namely, a charge from the crank case, a charge from the carburetor and a third charge entering from the crank case under pressure.

Internal combustion engines as hitherto constructed are not capable of forcing highly 40 voluminous charges, as above described, into their cylinders since the movement of the fuel and air mixture is too much retarded in and by the long way through the admission 45 passages and by the valves usually provided therein. It will be seen therefrom that the present invention is a remarkable advance in the art.

In the embodiment shown in Figures 3 and 4 the construction and arrangement of the 50 admission channel 9 including the branches 7 and 8, and the mode of charging are the same as described with reference to Figures 1 and 2 with the sole exception or difference that the exhaust valve is dispensed with and 55 an auxiliary piston 12 is substituted therefor for the purpose of controlling an exhaust port 13. The auxiliary piston 12 produces work in the same manner as the real working or main piston 5. The work, energy or movement of the two pistons is transmitted to a 60 shaft 17 by means of a spur gear system comprising the three wheels 14, 15 and 16, but the two pistons do not work in the same cycle, for the auxiliary piston 12 accomplishes two 65 strokes only during the time or period in

which the main or working piston 5 performs four strokes.

The co-operation of the two pistons 5 and 12 is diagrammatically shown in Figure 4, the arcs or segments A, A' denoting the working strokes, B, B' the exhaust strokes, C, C' the suction strokes and D, D' the compression strokes of the two pistons, respectively. Obviously the stroke C' of the auxiliary piston 12 is not a real suction stroke, since the 70 same counteracts the suction stroke of the working piston 5. This fact, however, is practically immaterial on account of the particular charging mode and the great, voluminous charge obtained thereby.

As the auxiliary piston is in advance of the main or working piston during the working stroke and consequently has gone considerably far beyond the inner dead centre at the time the explosion occurs, the working piston will be safely prevented from striking back, for instance, on starting the engine.

If the wheels 14, 15 and 16 are replaced by wheels such as 18, 19 and 20, respectively, as shown in Figure 3, and if the bearings of the shaft 17 are displaced to an amount as indicated by α , the two pistons will be adapted to work on the same cycle and the engine will run on the two stroke cycle method. Obviously a suitable sealing member must be substituted in such a case for the suction valve 21. A two stroke cycle motor is particularly useful in cases where the load is invariable whereas in case of load variation a four stroke cycle engine will be preferable. As regards manufacture the described two motor types are particularly advantageous inasmuch as they consist of and comprise the like individual parts or members.

In the modification illustrated in Figures 5 to 8 the engine comprises two cylinders *a* and *b* with pistons *c* and *d*, respectively. The pistons *c* and *d* are interconnected to move simultaneously in opposite phase of the cycle, that is to say, when the explosion occurs or the working stroke takes place in the cylinder *a*, fuel and air mixture will be drawn or sucked into the cylinder *b* or, in other words, the cylinder *b* will be charged at the same time, and vice versa, each time the working stroke is accomplished in the cylinder *b*, the cylinder *a* will be charged.

In Figure 7 it is supposed that the cylinder *b* is going to be charged. Now, when the pistons are moved in the directions indicated, respectively, by the arrows *e* and *f*, that is outwards, fuel and air mixture will be drawn in from a carburetor *g* through the branched channel *h* into the crank case *i* and the amount of fuel and air sucked in in this way will be equal to the volumes of the two cylinders swept by the pistons, taken together. Upon the subsequent movement of the two pistons inwards, that is in directions opposite

those indicated by the arrows *e* and *f* in Figure 7, the admission conduits are closed and the mixture in the crank case is compressed while at the same time a vacuum is produced 5 in the chamber *k* in front of the piston *d*. As the piston *d* continues to move inwards, a cup-shaped recess *l* provided in the outer peripheral wall of the piston, will coincide or register with the channel *h* and practically 10 at the same time with the outlet of a passage *m*, forming a communication between the cylinder and the admission valve *n*. The outlet of the passage *m* is located in close proximity to the outlet of the channel *h* and it 15 will be seen, upon inspection of Figures 5 and 6, that when the cup *l* reaches the point to register with the two outlets, the fuel and air mixture will flow from the carburettor *g* through the channel *h*, the cup *l*, the passage *m* and the admission valve *n* into the 20 evacuated chamber *k* in front of the piston *d*. As the piston *d* further continues to move in the direction towards the crank case the just described communication between the carburettor *g* and the chamber *k* will be cut off and communication between the chamber *k* and the crank case *i* will be established through or by means of a slot *o* provided 25 in the piston wall close by and in front of the cup *l* and adapted to coincide or register with the outlet of the channel *h* immediately after the cup *l* has passed over the same. As the mixture in the crank case is highly compressed due to the movement of the two pistons 30 towards the crank case, it will flow through the slot *o*, the passage *m* and the admission valve *n* into the chamber *k* which, at that time, already contains a full charge of fuel and gas of atmospheric or normal pressure. Figure 7 illustrates the position of the 35 parts or the moment at which gaseous mixture is going to be expelled from the crank case through the slot *o* into the passage *m*. It will be seen that in this manner the charge 40 of the cylinder will be increased to about three times the volume of the piston or still more. 45 As the cups *l* in the two pistons *c* and *d* are absolutely level with the outlets of the 50 passages *n* and *m*, the carburetor will simultaneously communicate through the cup *l* with the valves *n* of the two cylinders but the mixture formed by the carburetor flows only 55 into the combustion chamber of that cylinder which is just making the suction stroke. Although the slots *o* of each piston simultaneously coincide with the outlets of the passages *m*, the mixture compressed in the crank case 60 will also only flow over into the chamber *k* of the two cylinders which has received the normal suction charge and provide these chambers with an additional charge corresponding to the stroke displacement of the two pistons. 65 In the other cylinders, the overpressure of the explosion (or the controlling rods and

spring) keeps the suction valve closed. This operation takes place alternately in each cylinder.

It is apparent that the charging operation described with reference to the cylinder *b* likewise takes place in the same manner in the cylinder *a* of Figure 7, when the piston *c* performs its charging stroke while simultaneously therewith the piston *d* accomplishes its working stroke.

Obviously an engine constructed as hereinbefore described can be converted into a piston compressor without requiring considerable reconstruction, it being necessary only to remove or dispense with the carburettor and the rodwork controlling the exhaust valves. In Figure 8 we have shown a portion of a compressor equipped with an outlet or delivery valve *p* devoid of any actuating members and adapted to open towards the outer air and to be opened by the action of the compressed fluid during the compression stroke of the piston. During the suction stroke of the piston the delivery valve is held on its seat either by a suitable spring or by the overpressure in the delivery conduit. As regards the valve mechanism, therefore, the suction and delivery valves as usually employed in piston compressors, do not necessitate any change. In case of a multi-cylinder compressor a 95 separate crank case may be provided in connection with each single cylinder or any plurality of pistons working in the same direction may be provided with a joint crank case.

From the foregoing specifications it will be 100 seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claim.

What we claim is:—

Internal combustion engine of the four stroke cycle type comprising in combination a working cylinder with inlet for a fuel mixture and outlet for the waste gases, a working piston in the cylinder, a controlling piston for controlling the outlet in a further cylinder, the latter being arranged at an acute angle to the first named cylinder and having one common combustion chamber with the first named cylinder, each piston acting on an interchangeable driving wheel, an interchangeable central wheel engaging with both driving wheels and driven by the latter, a crank case also serving for preliminarily compressing the fuel mixture, a carburetor, a mixture supply conduit dividing into two branches, one branch opening into the inlet of the cylinder provided with a valve and the other valveless orifice completely smooth in 120 125 130

the interior opening into the cylinder wall at a considerable distance from the lower edge of the cylinder and being controlled by the inner edge of the working piston, a slot in
5 the piston wall of the working piston, a valve-
less overflow channel on the working cylinder and completely smooth in the interior and provided with an orifice opening into the
10 crank case and an orifice opening into the
15 working chamber of the cylinder permitting the mixture compressed in the crank case to pass over through the piston wall into the compression chamber of the cylinder when the first named orifice registers with the slot
in the piston wall.
